UNITED STATES PATENT OFFICE.

FRED S. SMITH, OF CINCINNATI, OHIO, ASSIGNOR TO THE BALDWIN COMPANY, OF CINCINNATI, OHIO.

MOUSE-PROOF PEDAL.

SPECIFICATION forming part of Letters Patent No. 788,438, dated April 25, 1905.

Application filed December 23, 1904. Serial No. 238,043.

To all whom it may concern:

Be it known that I, FRED S. SMITH, a citizen of the United States, residing at Cincinnati, in the county of Hamilton and State of Ohio, have invented new and useful Improvements in Mouse-Proof Pedals, of which the following is a specification.

My invention relates to improvements in the pedals adapted for use on pianos, organs, and other musical instruments; and the objects of my improvements are, first, to provide a simple device to prevent mice from getting into musical instruments through the openings provided for the pedals; second, to provide a device of the class stated with new and novel features, and, third, to provide a new article of manufacture—a device to prevent mice from getting into pianos, organs, and other musical instruments and which will add to the efficiency and appearance of the musical instrument without materially increasing the cost thereof. I attain these objects as illustrated in the accompanying drawings, forming a part of this specification, in which—

25 Figure 1 is a perspective view of the lower portion of an upright piano, showing my improvement. Fig. 2 is a cross-section of piano-pedal in normal position, showing the pedal-openings in the rail closed and protected. 30 Fig. 3 is cross-section showing the position of the pedal when in use.

Similar numerals of reference indicate corresponding parts.

Referring to the drawings, 1 is the lower 35 or pedal rail of a pianoforte, having openings 2 on the lower side of the same, through which the pedals 3 project. In this case I show two pedals, although any number of pedals may be used. The pedals 3 are mounted in the 40 ordinary way on the bottom board 4 and are adapted to be connected to the action of the piano, so as to control the dampers and other devices in common use. The pedal 3 is provided with a drop 5 of sufficient depth to cover 45 the opening 2 in the rail 1 when the pedal is in normal position, as shown in Fig. 2, and for the best results the pedal should be so mounted that the drop 5 is brought almost in contact with the face of the rail. A lip 6 pro-

jects inwardly from the lower edge of the drop 5 on a line parallel to the bottom edge of the pedal, the object of which is to completely close the opening in the rail 1 when the pedal is in its normal position, in which position the opening is greater than when the 55 pedal is depressed, as will be seen by reference to Figs. 2 and 3, owing to the difference in arc of circles described from the pivot-bearing of the pedal through the point where the drop 5 joins the pedal and the point where 60 the lip 6 is attached. The lip 6 also compensates for any variation in the projection of the pedals through the rail 1 due to expansion or contraction of the bottom board 4, to which the pedals are attached. The lip 6 can 65 be either cast integral with the pedal or made separately and attached to the pedal.

In order to make my device more effective, I use a pedal-guard 7, placed in the usual way on the front of the pedal-rail, said guard having a deep flange 8 projecting at right angles to the face of the same, said flange extending across the width of the rail 1 and resting on the upper surface of the bottom board 4. The guard 7 is provided with the usual openings 70 9, through which the pedals 3 project. It will be seen that the flange 8 of the guard 7 forms a plate which rests on the thin edge of the bottom board 4 and prevents mice from cutting their way through the same. 80

In case it is not desirable to place a pedal-guard on the rail 1 a metal plate may be used in lieu of the same, and when secured to the exposed upper edge of the bottom board in a position under the pedals it becomes equally 85 effective, in combination with the drop and lip of the pedals, in preventing the entrance of mice into the instrument.

Having described my invention, what I desire to secure by Letters Patent is— 90

1. A pedal for musical instruments having a drop and a lip projecting inwardly from the lower edge of said drop, substantially as described.

2. In a musical instrument the combination 95 with a pedal having a drop and a lip projecting inwardly from the lower edge of said drop of a bottom board, to which said pedal is at-

tached, said bottom board being protected at the exposed edge under the pedal with metal, substantially as described.

3. In a musical instrument the combination 5 with a pedal having a drop and lip projecting inwardly from the lower edge of said drop of a bottom board to which said pedal is attached, a pedal-rail, and a pedal-guard adapted to be attached to said rail, said guard having openings for the pedals and a flange projecting at right angles to the same, substantially as described.

4. In a musical instrument the combination with a pedal 3 having a drop 5 and a lip 6 pro-

jecting inwardly from the lower edge of said 15 drop, of a bottom board 4 to which said pedal is attached, a pedal-rail 1, and a pedal-guard 7 adapted to be attached to said rail, said guard having openings 9 for the pedals 3 and a flange 8 projecting at right angles to the same, 20 said flange being adapted to rest on the exposed edge of the bottom board 4 immediately under the pedal, substantially as described.

FRED S. SMITH.
